SHOE UPPER AND METHOD OF MANUFACTURE

Application filed May 19, 1930. Serial No. 453,508.

This invention relates to improvements in shoe manufacture and more particularly to an improved method of making and reinforcing shoe uppers and particularly the throat portions of shoe vamps, and to reinforced uppers of the type made in accordance with this improved method.

Heretofore the throat portions of shoe vamps have often tended to split due to the strains cast thereon during the lasting operation and occasionally these portions have split during subsequent use. In accordance with the present invention, a reinforcing strip is applied to the throat portion of the vamp effectively to receive the major portion of the strains cast thereon due to stretching, as for example in the lasting operation or due to subsequent strains in use. This reinforcing strip is preferably arranged so that it tends to impart a curvature to the vamp before it is lasted; accordingly the upper may readily conform to the curvature of the last, thereby facilitating the lasting operation and aiding in the proper shaping of the shoe and in its maintenance of such a shape. The reinforcing strip may be applied transversely of the throat portion, extending from one side to the other thereof, and being so disposed that it may engage the stitches securing the vamp to the top portions of a blucher shoe or a "bal" shoe, thus aiding in reinforcing the shoe during the lasting operation and throughout its life. Preferably the strip may be secured in adhesive engagement with the throat of the vamp by means of a cementitious coating that has previously been applied to the strip, for example a section of fabric or tape that has been coated with a permanently tacky or "cold process" adhesive, or which is provided with an adhesive that may be rendered tacky under heat may be employed for this purpose; in any case, the cement is preferably of a type that is strongly adherent.

In the preferred embodiment of the invention, the reinforcing strip is applied under tension to the vamp, thus tending to impart a curvature to the vamp even before it is lasted. Due to the relatively tensioned application of the reinforcing strip, the latter is adapted to receive and oppose the major portion of the stretching strains which may be imposed upon the throat of the vamp and which have previously been borne by the vamp itself, as for example during lasting. Accordingly, the uppers which are reinforced in this manner are strongly reinforced against splitting.

One advantageous method of applying the reinforcing strip to the vamp throat comprises the employment of a machine or apparatus provided with two driven rollers between which the vamp and adhesive strip are fed into mutually adhesive engagement with each other, the roll that engages and feeds the vamp being driven at a slightly higher peripheral speed than the roll which engages the strip so that the latter is applied under tension to the leather of the upper or the like. For example, convenient apparatus for performing this operation is a machine of the character disclosed in the copending application of Leland K. Butler, Serial No. 331,550, filed January 10, 1929, now Patent No. 1,787,138, issued December 30, 1930.

In the accompanying drawings: 75

Fig. 1 is an end elevation of apparatus which may be employed to apply the reinforcing strip to the vamp;

Fig. 2 is a plan view of a blucher vamp showing the reinforcing strip applied to the throat thereof;

Fig. 3 is a section on the line 3—3 of Fig. 2;

Fig. 4 is a view similar to Fig. 2 of a bal vamp; and

Figs. 5 and 6 are perspective views of shoe uppers, before lasting, showing the same reinforced in accordance with the present invention.

Referring to the accompanying drawings and first to Figs. 1 and 2 thereof, it is to be understood that the present invention involves the application of a transverse reinforcing strip 1 to the throat portion of a vamp 2, this reinforcing strip preferably being disposed adjoining the edge of the throat portion as shown and extending substantially transversely thereof. Such a reinforcing strip may conveniently be formed of a section of tape which has been coated with an agglutinant having relatively high adhesion. 101

Such a tape may preferably be applied under tension to the vamp so that the same even before lasting tends to have a normally concave curvature upon its inner face, i. e. the 5 face to which the reinforcing strip is applied. To permit this desirable result the tape may be fed into engagement with a lower presser roll 5 while the fabric may be fed into engagement with an upper presser 10 roll 6, these rolls both being positively driven, and a tape guiding instrumentality 7 being provided accurately to guide the tape to the bite of the rolls where it is engaged with the throat of the vamp. In order to effect 15 the tensioned application of the reinforcing strip the upper roll 6 which engages the vamp preferably may be formed of rubber and may rotate at a slightly higher peripheral speed than the lower roll 5, for example substantially 5% higher speed has 20 been found commercially satisfactory for this purpose. It is thus evident that the strip 1 is progressively applied under tension to the vamp 2 so that the reinforced vamp 25 as viewed in section may have a normal curvature substantially as shown in Fig. 4, thus tending to conform to the shape of the last.

As shown in Fig. 4, a reinforcing strip 1^a may be applied in the same manner to the 30 throat portion of a "bal" vamp 2^a rather than the blucher vamp shown in Fig. 2.

Fig. 5 shows the manner in which the 35 stitches 12 that secure the top portions 10 of a blucher shoe to the vamp engage the reinforcing strip 1, the stitches 12 curving upwardly from the bottom or edge portion of the vamp toward the throat and having end portions extending through the ends of the reinforcing tape. The stitching 13 that 40 secures the tongue 11 to the throat also has end portions 14^a passing through the reinforcing strip. Thus an unusually strong and effective reinforcement is provided which permits the vamp readily to conform to the 45 last and sturdily opposes splitting.

Fig. 6 shows an arrangement of the continuous stitching 14 which secures the top 50 portions 20 and tongue portion 21 of a "bal" shoe to the vamp, this stitching 14 adjoining the throat extending through the reinforcing strip 1^a, as shown in Fig. 6.

From the foregoing it is evident that this invention affords a shoe upper having the throat portion of the vamp effectively reinforced due to the firm adhesive engagement 55 of the reinforcing strip with the vamp as well as the engagement of the reinforcing strip with the stitching that secures the top portions and tongue in place. Furthermore, 60 the preferred manner of applying the reinforced strip aids in the proper shaping of the shoe upon the last and in the permanent maintenance of a proper shape. The tensioned application of the strip to the throat 65 of the vamp is particularly effective when

the vamp itself is formed of relatively yieldable material, such as leather, so that the strip receives the major portions of the strains tending to split this part of the shoe during lasting or in subsequent use.

I claim:

1. Method of reinforcing a shoe vamp, comprising progressively feeding the vamp and an adhesively coated reinforcing strip into adhesive engagement by a pair of presser rolls engaging and feeding the vamp and strip respectively, while rotating the roll engaging the vamp at a higher peripheral speed than that of the other roll, thereby imparting a concave transverse curvature to the vamp face to which the strip is applied.

2. A vamp having a throat portion, and a tensioned transverse reinforcing strip secured thereto for imparting a normal curvature to the reinforced vamp.

3. A vamp having a throat portion and a tensioned reinforcing strip extending transversely of said throat portion and adhesively secured thereto for causing the face of the reinforced vamp to which the strip is secured to have a normal transversely-concave curvature, whereby strains cast upon the throat are chiefly imposed upon the reinforcing strip.

4. A shoe upper comprising a vamp having a throat portion, a tensioned transverse reinforcing strip applied to said throat portion to impart a normal curvature to the reinforced vamp, a top portion, and stitching securing the top portion to the vamp and extending through the reinforcing strip.

5. A shoe upper comprising a vamp having a throat portion, a tensioned reinforcing strip extending transversely of said throat portion and adhesively secured thereto for causing the face of the reinforced vamp to which the strip is secured to have a normal transversely-concave curvature, a top portion, and stitching securing the top portion to the vamp and extending through the reinforcing strip.

6. A shoe upper comprising a vamp having a throat portion, a tensioned transverse reinforcing strip secured to said throat portion to impart a normal curvature to the reinforced vamp, a tongue, and stitching securing the tongue to the vamp, said stitching extending through the reinforcing strip.

7. A shoe upper comprising a vamp having a throat portion, a tensioned reinforcing strip extending transversely of said throat portion and adhesively secured thereto, for causing the face of the reinforced vamp to which the strip is secured to have a normal transversely-concave curvature, a tongue, and stitching securing the tongue to the vamp, said stitching extending through the reinforcing strip.

8. A shoe upper comprising a vamp having a throat portion, a tensioned transverse reinforcing strip adhesively secured to said throat portion to impart a normal curvature to the reinforced vamp, a top portion, a tongue por-

tion, and stitching securing said portions to the vamp and extending through the reinforcing strip.

9. A shoe upper comprising a vamp having a throat portion, said vamp being formed of relatively yieldable leather and a tensioned reinforcing strip of relatively unyielding material extending transversely of the throat portion and adhesively secured thereto, whereby strains imposed upon the throat portion are chiefly opposed by the reinforcing strip.
